UNITED STATES PATENT OFFICE.

MARY KAVANAGH, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,243, dated August 12, 1884.

Application filed June 23, 1884. Term of patent 3½ years.

To all whom it may concern:

Be it known that I, MARY KAVANAGH, of the city, county, and State of New York, have invented and produced a new and original 5 Design for a Pattern of a Lady's Costume, (numbered 9,306;) and I do hereby declare that the engraved prints accompanying this specification convey to any one accustomed to using paper patterns a clear understanding of how a 10 garment made up by the pattern will appear. The design shows a walking-skirt and an 15 overdress. The skirt exhibits a cluster of seven medium-deep tucks in its lower part. The overdress exhibits short tight-fitting vest-fronts, displaying a closing all the way down; partially-fitted polonaise-fronts displaying a gradual separation below the neck; two plaits back of the front edges at the neck

and draping plaits at the back edges below the waist-line, and assuming a deeply pointed 20 outline at their lower front corners; a closely-fitted polonaise-back exhibiting draping plaits in its front edges and at its middle seam, just below the waist-line, is rounding below the plaits in its left side edge, and shapes a deep 25 point at its lower right front corner; coat-sleeves, and a standing collar.

What I claim as my invention, and desire to secure by Letters Patent, is—

The design for a lady's costume, as shown in 30 the engraved prints accompanying this specification.

MARY KAVANAGH.
